UNITED STATES PATENT OFFICE.

FRANK L. SHADLEY, OF STERLING, NEBRASKA.

CAR-SEAL.

972,477.

Specification of Letters Patent.

Patented Oct. 11, 1910.

Application filed December 27, 1909. Serial No. 535,064.

To all whom it may concern:

Be it known that I, FRANK L. SHADLEY, a citizen of the United States, and a resident of Sterling, in the county of Johnson and 5 State of Nebraska, have invented certain new and useful Improvements in Car-Seals, of which the following is a specification.

My invention relates to self-locking car seals and has for its object to produce a 10 simple, cheap and efficient device of the character mentioned which shall provide absolute security.

My invention consists in certain novel features of construction, arrangement and combination of parts as will be hereinafter fully described and pointed out in the claims, reference being had to the accompanying diagram in which—

Figure 1 is a face view of my seal in its 20 locked position, Fig. 2 is a longitudinal section of the same on line 2—2 of Fig. 1, Fig. 3 is a similar section showing the location of parts just prior to final locking, Fig. 4 is a perspective view of the shackle or strap with 25 the keeper removed.

In carrying out my invention I take a single sheet metal strap A and near one end cut out an oblong portion leaving a slot A'; a short distance from said slot I strike up 30 a tongue A², the free end of which projects toward the slotted portion; I then bend back the strap as at a between said slot and tongue, leaving the bent end projecting rearwardly and horizontally as shown in Fig. 4. The 35 other end of the strap is provided with the substantially square opening B, and just in the rear of said opening B, a tongue B' is struck out the free end of said tongue projecting away from the opening B.

I provide a head or case C which consists of the plate C' having its outer end turned over as at c and the side edges turned over at c', these turned over edges forming a 40 guide to receive the edges c² of the top plate C² which are stamped so as to set below 45 the plane of plate C². Near the inner end of the top plate C² a portion is stamped or pressed out forming a socket C³, the purpose of which top will appear later on. The head 50 or case C is completed by associating the bottom and top plates C' and C² and the turned over edges c and c' mashed down over the edges c² of the top plate C² and then soldered, making the head or case a rigid rectangular keeper open only at its rear end.

To use my improved device the strap or

shackle is passed through the staple on the car door and the end having the turned back portion in which is the slot A' is forced into the case C as shown in Fig. 3 until the bent 60 end a strikes against the end of the case; the tongue A² will spring up into the slot A', the end of the strap having the slot B is now inserted into the case C, said end sliding on the end A until it reaches the tongue A² which 65 it forces downwardly until the slot B passes over said tongue A² where the tongue springs upwardly through the slot B and into the slot A' again: while this action is taking place the spring tongue B' has passed 70 beyond the rear end of the turned back portion of the end A and springs upwardly through the slot A' and into the socket C³ and rests on the edge of the slot A' as shown in Fig. 2; the edge of the top plate C² is turned in 75 to form a recess or seat c³ within which the end of the turned back end will lie and prevent the withdrawal of the interlocked ends of the strap from the head, as is plainly shown in Figs. 2 and 3.

It will thus be seen that I produce a simple, cheap and positive seal which can only be opened by destroying the same, so that tampering with same will readily be discovered.

I claim—

1. A seal comprising a casing or head and a sheet metal shackle, said shackle having bent back portion at one end, said bent back portion having an elongated slot therein, 90 and a tongue projecting from the strap below said slot, the other end of the shackle having an opening near its free end and a rearwardly projecting spring tongue in the rear of said opening, the head or casing having a socket in its upper face to form a seat for the end of the last mentioned spring tongue and retain the shackle within the casing or head.

2. In a car seal the combination with a 100 strap, a shackle having one end bent back and slotted longitudinally, a spring tongue projecting upwardly from said strap below the slot, the other end portion of the strap having an opening near its free end, a spring 105 tongue projecting rearwardly from the strap adjacent to said opening, and adapted to project through the longitudinal slot in the bent over end of the strap, and a head or casing to receive the interlocked ends of the 110 shackle, said casing having a socket in its upper wall to receive the end of the rear-

wardly projecting spring tongue, the rear edge of the upper wall of said casing bent downwardly and inwardly to form a seat for the end of the said turned back end, to prevent withdrawal of the interlocked ends of the shackle from the casing or head.

3. In a car seal, the combination with a casing or head comprising an open ended box, the upper wall of which is provided with a socket, and the rear end of said upper wall bent downwardly and inwardly to form a rest or socket, of a shackle or strap having

two ends, one of which is bent back, said ends having oppositely projecting spring tongues and slots through which said tongues project, said ends adapted to be inserted in the aforesaid casing or head, the seat or socket in the upper wall of the casing adapted to prevent withdrawal of the interlocked ends of the shackle or strap.
